UNITED STATES PATENT OFFICE.

FRANK F. SMITH, OF NEWARK, NEW JERSEY.

SASH-PULLEY.

1,017,114.

Specification of Letters Patent. Patented Feb. 13, 1912.

Application filed August 28, 1911. Serial No. 646,541.

To all whom it may concern:

Be it known that I, FRANK F. SMITH, a citizen of the United States, residing at Newark, in the county of Essex and State 5 of New Jersey, have invented certain new and useful Improvements in Sash-Pulleys, of which the following is a specification.

My present invention relates to an improved construction of sash-pulley intended 10 particularly for use in connection with fire-proof windows, and especially adapted to be made of malleable iron castings. Its advantages of simplicity and of inherent strength, both of construction and of the 15 materials of which it is adapted to be made, will be appreciated by those skilled in the art from an understanding of the following description in connection with the drawings.

20 In the drawings showing one of the specific forms, which my improved construction may take, Figure 1 is a side elevation of my sash-pulley shown complete in assembled position on the corner of a sheet-metal window frame, said frame being 25 shown in vertical section. Fig. 2 is a side elevation of the housing-part of the construction shown separate from the other parts. Fig. 3 is an underneath plan view 30 of said housing-part, that is a view looking at said part from below in Fig. 2. Fig. 4 is a side elevation of the fork-part of the construction shown separate from the other parts. Fig. 5 is a rear elevation of the 35 fork-part, that is a view looking at said part from the right in Fig. 4. Fig. 6 is a side elevation of the pulley detached, and Fig. 7 is a plan view of its axle-pin.

I will now describe the device of the 40 drawings, reserving it to the claims to point out the novel features and to define the scope of the invention, it being understood that the claims will be given the due range of equivalents to which they may be entitled in view of the art.

45 My improved sash-pulley construction consists of two main parts, namely a housing-part 1 and a fork-part 2, together with a grooved sash-pulley 3 having an axle-hole 3^a through it, and an axle-pin 4 adapted to be received through the hole 3^a with bearing fit so that the pulley rotates on the pin 4 as an axle.

50 The housing-part 1 consists of a hollow hood or housing 1^a, which rotatably supports within it the sash-pulley 3 as will be

hereinafter described and as is shown in Fig. 1. The sash chain or cord runs over the grooved periphery of this pulley and between it and the surrounding interior of 60 the housing to connect on the one side with the sash and on the other with the sash weight in the same manner which is common and well understood in the art, and is, therefore, not illustrated.

65 The housing-part 1 in addition comprises a strap 1^b extending rearwardly from the bottom of the housing 1^a and is provided with a bolt-hole or holes 1^c which may be single or plural, round or elongated as 70 shown. Further this strap is provided with bolts 1^d or other securing means adapted to these holes for securing the strap 1^b to the upper side of the corner of the window frame. In the drawings the undersides of 75 the holes 1^c are countersunk to correspond with the heads of the bolts so that on taking up on the nuts of the bolts the sheet-metal 5 of the window frame is drawn into the countersunk portions of the bolt-holes in 80 the strap to permit the heads of the bolts to become themselves countersunk so that the tops of the heads are substantially flush with the exposed face of the sheet-metal 5. However, this countersinking is a mere 85 detail of construction, for which no invention is claimed. Finally, the sides of the housing 1^a are provided with a pair of 90 grooves 1^f which in direction extend transversely to the length of the strap 1^b, these 95 grooves consisting of the spaces between the ridges 1^g formed on the sides of the housing, and extending through the bottoms of the grooves 1^f are holes adapted to receive through them the axle-pin 4 to support 95 the pin and its pulley in operative position in the housing as shown in Fig. 1.

The housing-part 1 consisting, as described, of the hollow hood 1^a, strap 1^b and the grooves 1^f formed between the ridges 1^g 100 is adapted to be made of a single malleable iron casting.

105 The fork-part 2 of the construction consists of a strap 2^a having countersunk holes 2^b provided with bolts or other securing means 2^d, in substantial correspondence with the similar devices already described in connection with the strap 1^b of the housing-part. The fork-part takes its name from the fork 2^f on the upper end of the strap 2^a. 110 The planes of the terms of this fork are transverse to the plane of the strap 2^a.

Further they are adapted to straddle the sides of the housing 1^a and in doing so are received slidably into the grooves 1^f. The arms 2^f preferably taper slightly toward their free ends as do also the sides of the grooves 1^f, with the result that the parts when engaged tend to fit together more snugly and tightly than they would do if the parts engaged on parallel lines. The 10 arms 2^f have holes 2^g through them which align with the holes 1^g in the sides of the housing when the parts are assembled together as in Fig. 1. The result is that when the axle-pin 4 is inserted through the holes 15 2^g and 1^g of the fork and housing-parts as well as through the hole 3^a in the pulley and is "upset" at its ends, it permanently unites all of the parts of the sash-pulley construction at the same time that it forms the axle 20 on which the pulley 3 rotates.

It will be noted from Figs. 1 and 4 that the inner face of the strap of the fork-part 2 is preferably provided with a transverse recess 2^x, which is adapted to receive into 25 it the joint 8 formed by the interlocked edges connecting the pieces of sheet-metal at the corner of the window-frame. It will be seen that the fork-part is also adapted to be a malleable iron casting.

30 What I claim is:

1. The improved sash-pulley construction consisting of a housing-part, a fork-part, a sash-pulley and an axle-pin, the housing-part consisting of a housing adapted to operatively contain the sash-pulley and having a strap extending rearwardly from its base, the sides of the housing having grooves which extend transversely to the length of the strap, and said fork-part consisting of 35 a strap having a fork at one end whose arms slidably enter the grooves in the sides of the housing, the arms of the fork and the sides of the housing having holes through them which are in alignment when the housing and fork-parts are assembled together to receive through them the axle-pin which likewise operatively supports the pulley in the housing, and securing means on said straps for securing them and the entire construction to the corner of the window-frame.

50 2. The improved sash-pulley construction consisting of a housing-part, a fork-part, a

sash-pulley having an axle-hole there-through, and an axle-pin, the housing-part consisting of a hollow housing adapted to 55 contain the sash-pulley and having a strap extending rearwardly from the bottom of the housing, the sides of the housing having grooves extending transversely relatively to the strap and the sides of said grooves converging toward the top of the housing, and 60 said fork-part consisting of a strap having a fork at one end the planes of whose arms are transverse to the plane of the strap, the sides of said arms converging toward 65 their free ends to slidably enter endwise the grooves in the sides of the housing, the arms of the fork and the sides of the housing having holes through them, which are in alignment when the housing and fork-parts 70 are assembled as described to receive through them the axle-pin which likewise passes through the axle-hole in the pulley to operatively support it in the housing, the aforesaid straps being provided with securing means for securing them and the entire construction to the corner of the window-frame.

3. The improved sash-pulley construction consisting of a housing-part, a fork-part, a 80 sash-pulley and an axle-pin, the housing-part consisting of a housing adapted to operatively contain the sash-pulley and having a strap extending rearwardly from its base, and said fork-part consisting of a strap having a fork at one end whose arms straddle the sides of the housing when the housing and fork-parts are assembled together, the arms of the fork and the sides of the housing having holes through them which are in 85 alignment when the parts are assembled together, said holes receiving through them the axle-pin which likewise operatively supports the pulley in the housing, and securing means for securing the straps and the 90 entire construction to the corner of the window-frame.

In testimony whereof I affix my signature in presence of two witnesses.

FRANK F. SMITH.
